BOOM STOP

Thomas W. Thomas, San Rafael, Calif.

Application August 9, 1943, Serial No. 497,957

4 Claims. (Cl. 212—39)

This invention relates to improvements in power releasing devices, and has particular reference to a device for releasing the power as applied to a crane boom.

The principal object of this invention is to provide means for automatically stopping a crane boom at a predetermined point on its upward travel.

A further object is to provide means whereby the boom can be lowered after it has been stopped.

A further object is to provide a device of this character which may be applied to any standard form of crane boom without materially altering its construction or operation.

A further object is to produce a device which is economical to manufacture and one which will not become deranged in use.

Other objects and advantages will be apparent during the course of the following description.

In the accompanying drawings forming a part of this specification and in which like numerals are employed to designate like parts throughout the same,

Fig. I is a diagrammatic illustration of my device as the same would be applied to a crank boom and its operating mechanism.

Fig. II is a side elevation of the boom contact and air release cylinder and shown partly in cross section.

Fig. III is a side elevation of the foot pedal and resetting cylinder and shown partly in cross section.

Cranes are used for the purpose of handling heavy loads and comprise a power mechanism, which in turn drives gears through a master clutch. The gears in turn actuate drums, over which cables pass, which cables are used for elevating the boom and handling the load.

Cranes are usually mounted upon portable carriages, whereby the crane as a whole may be moved from place to place in transporting the load.

It often occurs that an operator will neglect to disconnect the boom-lifting mechanism while the crane is being propelled over its course of travel, the result being that when the boom moves upwardly to a predetermined angle, it will engage a fixed stop on the supporting structure and further movement of the boom will be arrested. If the hoisting mechanism continues to exert a pull on the boom, the boom will be bent over backwards, endangering the life of the op-

erator, distorting the boom and causing considerable damage.

I have, therefore, devised a mechanism which may be attached to the ordinary crane in alignment with the boom, whereby when the same does reach a predetermined elevation, a contact will be made which will release the driving mechanism, thus arresting any further movement of the boom, which will prevent damage thereto, and thus save costly repair bills as well as loss of the use of the crane during the repair period.

Referring to the drawings in detail, particularly Fig. I, the numeral 5 designates the lower end of a pivoted boom, pivoted as at 6.

10 15 The hoisting mechanism has been omitted, in order to simplify the drawings.

At 7 I have shown a power unit which drives a shaft 8 through a master clutch 9, which may be manually operated by a lever 11, or through the use of a booster, cylinder and piston, as shown at 12. A compressor 13 delivers compressed air to a storage tank 14.

20 25 The parts thus far described are common to all crane arrangements, whether they be gasoline driven or electrically driven.

My invention comprises the employment of a pair of cylinders, one of which is the air-release cylinder 16, and the other a resetting cylinder 17. The air-release cylinder 16 is mounted upon 30 the cab of the crane or in any other convenient place, whereby the head 18 is in alignment with a pad 19 mounted on the boom 5.

The head 18 is mounted on the end of a valve rod 21, which enters the cylinder 16 and has a 35 valve 22 formed upon its opposite end. This valve in turn normally seats on a seat 23 formed in a division wall 24 within the cylinder 16, which wall forms chambers A and B. A spring 26 normally holds this valve in its seated position.

40 45 A pipe 27 conducts air from the tank 14 to the chamber A of the cylinder 16.

A pipe 28 connects the chamber B of the cylinder 16 with the chamber C of the cylinder 17. This cylinder likewise has a division wall, as shown at 29, which is provided with a valve seat 31, against which a valve 32 is adapted to seat.

50 55 This valve 32 is carried on a valve rod 33 passing through the end of the cylinder 17 and terminating in a head 34, against which the bifurcated end 36 of a foot pedal 37 contacts, the pedal being pivoted as at 38.

A spring 39 positioned within the chamber D normally maintains this valve 32 out of contact 60 with its seat 31.

A pipe 41 connects the chamber D with the booster cylinder 12, the piston of which is in turn connected to the master clutch mechanism through the linkage 42.

The result of this construction is that when the crane is being operated and if the boom is elevated to a point where the pad 19 engages the head 18, then inward movement of the head against the tension of the spring 26 will move the valve 22 away from its seat 23, thus permitting air from the tank 14 to pass through the pipe 27 through the chamber A into the chamber B through the pipe 28 into the chamber C, past the open valve 32 into the pipe 41 and into the booster cylinder 12, with the result that the booster cylinder will actuate the master clutch, releasing the power from the gear and cable mechanism, thus instantly stopping any further upward travel of the boom.

As this air is under very high pressure, its travel from the static state in the cylinder A to the booster cylinder 12 is very rapid, so that an almost instantaneous stoppage of the hoisting of the boom occurs.

The booster 12 is provided with a constantly open bleeder 43; therefore, in order to reset the mechanism so that the boom may be lowered and the clutch released, the operator steps upon the foot pedal 37, which moves the bifurcated end against the head 34, which pulls the valve 32 to a closed position, thus preventing any further passage of air from the tank 14 to the booster.

The bleeder now serves to release pressure in the booster cylinder and enables the operator to manually throw the master clutch to engage the power.

As soon as the boom starts to travel away from the air release cylinder the spring 26 functions to close the valve 22 against its seat 23, after which the operator may remove his foot from the foot pedal, and the mechanism will again be in normal working condition.

It will thus be seen that by applying this simple mechanism to any ordinary crane, or similar mechanism having a movable member, it is possible to prevent damage to the movable member, thus eliminating expensive repairs, loss of the use of the crane during the repair period and providing protection to the operator against physical injury.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. In a fluid pressure-actuated limit stop for the control clutch of a hoist boom, a cylinder having a partition therein dividing the same into two separate chambers with one of said chambers in constant communication with a source of compressed air, a valve in said partition having a tensioned rod extending through one end of the cylinder and adapted to be operated for inserting said valve, a second cylinder having a par-

tition therein forming two chambers and having a valve seat, with a tensioned normally inserted valve therein, means forming communication between one end of the second cylinder and the chamber of the first cylinder normally out of communication with the source of compressed air, a control clutch, clutch actuating mechanism, means forming communication between the second cylinder and the clutch actuating mechanism and manually operated means for closing the valve in the second cylinder for closing communication between the second cylinder and the clutch actuating mechanism.

2. In a fluid pressure actuated limit stop for the control clutch of a hoist boom, a source of power and a master clutch, a pair of cylinders in communication with each other, a source of compressed air in communication with one cylinder and means forming communication between the other cylinder and the master clutch, a control valve in the cylinder communicating with the source of compressed air and normally shutting off communication between the two cylinders and adapted to be operated by a boom to form communication between the two cylinders whereby compressed air may flow through the second cylinder for the operation of the operating means for the master clutch and means for shutting off communication between the second cylinder and the master clutch.

3. In a fluid pressure actuated limit stop for the control clutch of a hoist boom, a source of power and a master clutch, a pair of cylinders in communication with each other, a source of compressed air in communication with one cylinder and means forming communication between the other cylinder and the master clutch, a control valve in the cylinder communicating with the source of compressed air and normally shutting off communication between the two cylinders and adapted to be operated by a boom to form communication between the two cylinders whereby compressed air may flow through the second cylinder for the operation of the operating means for the master clutch and manually operated means for shutting off communication between the second cylinder and the master clutch.

4. In a fluid pressure actuated limit stop for the control clutch of a hoist boom, a source of power and a master clutch, a pair of cylinders in communication with each other, a source of compressed air in communication with one cylinder and means forming communication between the other cylinder and the master clutch, a control valve in the cylinder communicating with the source of compressed air and normally shutting off communication between the two cylinders and adapted to be operated by a boom to form communication between the two cylinders whereby compressed air may flow through the second cylinder for the operation of the operating means for the master clutch and manually operated means for shutting off communication between the second cylinder and the master clutch comprising a pedal operated valve in the second cylinder.

THOMAS W. THOMAS.
